Attas

It is an object of my invention to eliminate the use of a stencil and to substitute a porous metal drum which may be inked and which may be used in a duplicating machine to produce a uniform film of ink on the under surface of a sheet of paper or the like, which film may be used in a duplicating machine to produce a uniform reproduction of the original.

UNITED STATES PATENT OFFICE

This patent relates to a duplicating machine, and more particularly to improvements in the inking means thereof.

DUPLICATING MACHINE

Herbert P. Sherman, Chicago, Ill.

Application February 14, 1950, Serial No. 144,158

(Cl. 101—119)

1. *Apparatus and Method.*

My invention relates to a duplicating machine of the type employing stencils, and more particularly to improvements in the inking means thereof.

Heretofore, in duplicating machines of the type described, the stencils were stretched over and supported on the face of a rotatable drum, the face of which was perforated over an area substantially coextensive with that of the stencil and was covered with a fabric blanket against which the stencil was placed. A quantity of suitable ink was introduced, through an opening, into the drum interior and, in the course of rotation of the drum, the ink was caused to pass through the perforations to wet the fabric blanket which acted in the nature of a wick to conduct the ink to the stencil from which it was deposited on a sheet of paper or the like.

The foregoing type of stencil drum had certain disadvantages among which was the constant escape of the ink, during the operation of the machine, along the edges of the stencil. This was, in the main, due to the pressure of a co-operating roller against the drum which tended to accumulate, immediately in advance of the line of contact of the roller with the drum, under the stencil, a mass of ink which increased progressively in quantity with each increment of rotation of the drum. Since no satisfactory means was provided for the return of the ink to the interior of the drum, the ink escaped along the edges of the stencil. Another disadvantage was the necessity for positioning the drum in a particular position when the machine was not in use so as to prevent the escape of ink through the perforations in the drum. A further disadvantage was the necessity for cleaning the fabric blanket after each use so that the blanket would not become clogged with ink pigment and thereby impair the wicking action thereof.

Accordingly, it is an object of my invention to provide an improved drum construction in which is eliminated the use of a perforated drum face and a fabric wicking blanket stretched thereover, and instead thereof, is provided a drum face formed of porous metal through which the ink may pass by capillary action, to the stencil. Thus, the plate of porous metal controls the amount of ink contacting the stencil and prevents the accumulation of excessive quantities of ink which results in dripping.

A further object of my invention is the provision of an inking surface which is smooth and which deposits a uniform film of ink on the under surface of the stencil, resulting in reproductions which are all of uniform quality.

2. *Apparatus and Method.*

A still further object of my invention is the provision of a drum face which is easily cleaned and more durable than the fabric blankets of prior art devices which require replacement at frequent intervals.

A still further object of my invention is the provision of an improved drum so constructed that excessive ink is absorbed by an absorbent member and, in the course of operation of the machine, the ink is returned to the interior of the drum through expression of the ink from the absorbent member.

Other and further objects and advantages of my invention will become apparent from the following description when considered in connection with the accompanying drawings in which:

Fig. 1 is an elevational view of a duplicating machine embodying my invention.

Fig. 2 is a vertical cross sectional view taken substantially on line 2—2 of Fig. 1, the said view being on an enlarged scale.

Fig. 3 is a cross sectional view taken substantially on line 3—3 of Fig. 2.

Fig. 4 is a fragmentary view similar to Fig. 3 but showing the drum and pressure roller in another relative position.

Fig. 5 is a bottom plan view looking upwardly in the directions of the arrows 5—5 of Fig. 3.

Fig. 6 is a perspective view of a detail.

Referring to the drawings, the numeral 10 indicates generally a duplicating machine comprising a base structure 11, a stencil carrying drum, indicated generally at 12, a reciprocating pressure member 13 acting on the stack of sheets 14 to effect a displacement of only the top sheet of the stack at any one time, and a pressure roller 16, spring biased, so as to exert an upward thrust and to engage the underside of a sheet on which a reproduction is to be made to urge the same against the stencil carried on the drum 12.

My invention is directed specifically to the construction of the drum 12 and its manner of operation. Referring particularly to Figs. 2 to 5 inclusive, the drum of my invention is shown as comprising dished end members 17 and 18 of identical construction, each being formed with an annular flange 19, the end portion of which is reversely bent as at 21 in offset relation to the flange 19 to provide a space therebetween and is further bent upwardly to provide a flange 22 in a vertical plane. The end members 17 and 18 are formed substantially as shown in elevation in Fig. 3, with the portion AC progressively decreasing in radius from point A to point C. The peripheral edge of each of the members 17 and 18 between the points B and C are recessed, as at

23, for a purpose, as will be hereinafter described.

It is to be understood that the flange construction, above described and illustrated more clearly in Fig. 2, extends completely around the peripheral edges of the end members 17 and 18. The said members 17 and 18 are suitably mounted on a shaft 24 to rotate therewith, the said shaft being suitably journaled in end members 26 of the base 11. A crank arm 27 is fixed to the shaft 24 and is adapted for rotating the said shaft and with it the drum 12.

Supported on the flanges 19 and extending substantially from point A to point B is a plate member 28, the said plate member being in the form of a metal sheet having a quality of porosity such that ink may pass therethrough. I have found that a product manufactured by the Chrysler Corporation, Amplex Division and sold under the trade-mark of "Oilite" functions to produce highly desirable results. The said material is a bronze alloy which has been processed according to methods well-known in powder metallurgy. It is to be understood, however, that my invention is not limited to the use of the particular "Oilite" product but is directed to the use of a metal sheet which has the desired porosity so that ink may pass therethrough, from one side to the other, to supply ink to a stencil 25 which is adapted to lie contiguous to the outer surface of the said plate.

A second imperforate plate member 29, preferably of sheet metal is supported on the flanges 19 and extends from points B through C to A so as to provide a continuous face with the member 28 for the drum 12. The marginal edges of the plate member 29, like those of the member 28, are received in the peripheral recesses of the end members 17 and 18 and are sealed therewith, as with solder, to provide a water-tight joint. The plate member 29 follows the contour of the peripheral edges of the recessed portions 23 of the end members 17 and 18, as viewed in Fig. 3, so as to form a longitudinally extending trough in which is received the absorbent material hereinafter to be described. The trough is provided with an elongated slot or a plurality of apertures 30 for a purpose as will be hereinafter explained.

Attached to the plate member 29, as by rivets, is a strip 31 having struck out from the plane thereof, a plurality of hook like elements 32 which are adapted to engage in the apertures provided at the end of stencil 25 to secure the same to the drum face. A substantially U-shaped member 33 is riveted to the face of the member 29 and is formed with a longitudinal portion 34. The said member preferably is formed of a resilient metal and is arranged to bear against the surface of the member 29 and to secure the other end of the stencil 25 between the longitudinal portion 34 and the surface of the member 29. Thus, the stencil 25 is held securely and maintained in taut condition while on the drum. In order to facilitate insertion or removal of the end of the stencil from the drum, an L-shaped wire element 36 is provided, the said element having offset portions 37 which are adapted to engage under the legs of the U-shaped member 33 so that when the lever arm 38 of the wire element is moved, a camming action is effected which temporarily lifts the portion 34 from the surface of the plate member 29 so as to provide a space therebetween.

The drum 12 is provided with a filling aperture 39 through which ink may be admitted into the

interior of the drum. A cap 41 serves to provide a closure for the said aperture.

The absorbent material may comprise felt or any suitable absorbent material and may be in the form of an elongated body member 42 having a form similar to that illustrated in Fig. 6. The absorbent member 42 is held in position by a retaining member 43 having end walls 45 and resilient end clips 44 which are adapted to engage the side members 17 and 18 of the drum and to frictionally retain the absorbent member 42 within the recess 23. It will be apparent that slight movement of the retaining member 43, radially of the drum, thus, is possible because of the frictional engagement of the clips 44 with the end members 17 and 18.

The operation of my device should be understood from the foregoing description, but briefly stated it is as follows:

A quantity of ink is introduced within the interior of the drum 12 and with a stack of sheets or cards 14, arranged as illustrated in Fig. 1, the lever 27 is rotated to effect a complete revolution. It is of course understood that the drum 12 has been rotated previously a number of times in order to permit the ink to permeate through the porous plate 28 and to distribute itself over the surface thereof. Printing or duplicating on a blank sheet is effected in a well-known manner. During the course of operation, as a result of the action of the cooperating roller 16 against the stencil 25, in each turn of the drum, a mass of ink may accumulate between the stencil 25 and the porous plate 28, the mass of ink increasing progressively in amount until the roller 16 reaches point B adjacent the recess 23. At this point, the ink is caused to flow into the recess 23 and to be absorbed by the absorbent member 42. In the course of further rotation of the drum, after the absorbent member has become saturated with ink, the cooperating roller 16, in pressing against the said absorbent member, acts to express the ink therefrom and to force the same through the slot 30 in the recess 23, thereby returning the ink to the interior of the drum for further use. It will thus be apparent that dripping of the ink from the drum is completely obviated, thereby resulting in a more economical and cleaner operation of the machine. I have found that a porous metal plate of the type described has the property of allowing just the right amount of ink to pass through to the stencil to obtain a clear impression of the stencil on the paper.

I claim:

1. In a duplicating machine of the type described, a rotatable substantially cylindrical drum adapted to support a stencil, said drum comprising end members each having a substantially semicircular portion, an adjacent arcuate portion of progressively decreasing radius of curvature and a recessed portion connecting said two first mentioned portions, a porous plate through which ink may pass by capillary action arranged between said semi-cylindrical portions and constituting a portion of the face of said drum, a non-porous plate arranged between said arcuate and said recessed portions and constituting the remainder of the face of said drum, said non-porous plate having an aperture therein aligned with said recessed portion, a mass of absorbent material adjacent the face of said drum at said recessed portion, and means for securing a stencil contiguous to said porous plate.
2. In a duplicating machine of the type de-

scribed, a rotatable substantially cylindrical drum having a face one portion of which is substantially semi-circular in profile and of such porosity that ink may pass therethrough by capillary action, means for securing a stencil in contiguous relation to said face portion, said face having an adjacent non-porous portion which is arcuate in profile and of progressively decreasing radius of curvature, said face also having a recessed portion connecting said arcuate and semi-cylindrical portions, said recessed portion having an aperture therein, and a mass of absorbent material within said recessed portion.

3. In a duplicating machine of the type described, a rotatable substantially cylindrical closed drum adapted to contain ink therein and having a face a portion of which is of such porosity that ink may pass therethrough by capillary action, means for securing a stencil contiguous to said porous face portion, said drum having another face portion which is recessed inwardly to form a longitudinal trough, said trough having an aperture therein affording communication with the interior of said drum, and a mass of absorbent material supported in said recessed portion and adapted to absorb excess ink expressed from between said porous plate and said stencil.

4. In a duplicating machine of the type described, a rotatable substantially cylindrical closed drum adapted to contain ink therein and having a face a portion of which is of such porosity that ink may pass therethrough by capillary action, means for securing a stencil contiguous to said porous face portion, said drum having another face portion which is recessed inwardly to form a longitudinal trough, said trough having an aperture therein affording communication with the interior of said drum, and a mass of absorbent material supported in said recessed portion and adapted to absorb excess ink expressed from between said porous plate and said stencil, and a roller cooperating with said drum to express ink from said absorbent mass through said aperture and into said drum.

5. In a duplicating machine of the type described, a rotatable substantially cylindrical drum having a face one portion of which is substantially semi-circular in profile and of such

porosity that ink may pass therethrough by capillary action, means for securing a stencil in contiguous relation to said face portion, said face having an adjacent non-porous portion which is arcuate in profile and of progressively decreasing radius of curvature, said face also having a recessed portion connecting said arcuate and semi-cylindrical portions, said recessed portion having an aperture therein, and an absorbent member removably received within said trough, said absorbent member substantially filling said trough and being adapted to absorb excess ink expressed from between said porous plate and said stencil.

6. In a duplicating machine of the type described, a rotatable substantially cylindrical closed drum adapted to contain ink therein and having a face a portion of which is of such porosity that ink may pass therethrough by capillary action, means for securing a stencil contiguous to said porous faced portion, said drum having another face portion which is recessed inwardly to form a longitudinal trough, said trough having an aperture therein affording communication with the interior of said drum, an absorbent member removably received within said trough, said absorbent member substantially filling said trough and being adapted to absorb excess ink expressed from between said porous plate and said stencil, and a roller cooperating with said drum to express ink from said absorbent member through said aperture and into said drum.
